UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed November 18, 1924 Serial No. 750,590.

This invention aims to provide an improved separable fastener, particularly, though not exclusively, useful in securing carpets and the like to floors.

5 In the drawings, which illustrate a preferred embodiment of my invention:—

Figure 1 is a plan view of one corner of a carpet showing an underlying fastener in dotted lines;

10 Fig. 2 is a section on the line 2—2 of Fig. 1, being partly in elevation;

Fig. 3 is a top plan view of the preferred form of socket;

15 Fig. 4 is a bottom view of the socket shown in Fig. 3;

Fig. 5 is a section on the line 5—5 of Fig. 3; and

Fig. 6 is a section on the line 6—6 of Fig. 3.

Referring to the drawings and to the preferred form of my invention, I have shown a socket pressed from a single sheet of metal and presenting an outer upstanding cylindrical wall 1 having extending therefrom a plurality of attaching prongs 2, similar to those shown and described in my copending application Serial No. 687,753.

20 A second or inner upstanding cylindrical wall 3 is also provided and both walls are connected at their lower peripheries by a web 3^a, as best illustrated in Figs. 2 and 4.

The inner wall 3 supports, at its upper periphery, a plurality of resilient fingers 4 between which are provided alternating short slots 5 and long slots 6, the purposes of

25 which are more fully hereinafter described.

The resilient fingers extend curvilinearly downward from the upper periphery of the inner wall 3 to the plane of the web 3^a and then upwardly to the plane of the upper periphery of the wall 3 where they terminate to form a stud-receiving aperture 7 for reception of the head of a stud. These resilient fingers are provided at their free ends with reversely bent neck-engaging portions 8 for cooperative engagement with the neck of a stud.

30 The short slots 5 and long slots 6 provide the plurality of resilient fingers 4 having lengthwise edges of unequal length so that they may flex upon substantially straight lines extending between the outer ends of the slots. These lines are located along such points in the socket as to permit the greatest flex of the fingers it being easier to flex the 35 fingers on a straight line between the slots

than on a curved line as would be the case if the slots were all terminated at the upper end of the wall 3. To accomplish the foregoing results the slots 6 extend to the inner wall 3 (Fig. 6) and the slots 5 fall short of the wall 3 (Fig. 5), thereby permitting the resilient fingers 4 to flex upon substantially straight lines where the metal of the socket has not, to any great extent, flowed or stretched, thereby providing fingers of maximum durability. The downward and upward curve of the resilient fingers greatly increases their strength as well as their length, thus greatly decreasing the amount which the outer ends of the fingers must flex during 40 engagement and disengagement of the stud.

The socket may be attached to the carpet 45 by the attaching prongs 2, in much the same manner as described in the above-mentioned copending application.

50 The preferred form of stud, for use in connection with the above described socket, is formed from a single piece of metal turned or otherwise shaped in a suitable machine to present the usual head 10, shoulder 11, neck 12 located between the head and shoulder and a relatively long shank or attaching portion 13 slightly tapered. The stud is preferably secured to the floor 14 of an automobile or the like, by forcing the attaching portion 13 into 55 a hole 15 therein of approximately the same diameter as the small end of the attaching portion 13 of the stud. Thus the attaching portion of the stud is wedged into the hole 15 and is held therein by the friction between the 60 wood and shank. To prevent driving the shoulder 11 of the stud into the wooden floor, I have interposed a metal washer 16 between the shoulder 11 and the floor 14, which spreads out over sufficient area to prevent its being 65 pressed into the floor. This type of stud is simple and inexpensive to manufacture and may be quickly and easily attached to the floor, and when attached it grips the side walls of the hole so tightly that it is capable 70 of withstanding great upward strain exerted thereon. The surface of the attaching portion 13 may, if necessary, be roughened slightly to increase the grip on the wall of the hole 75 in the floor.

80 When the socket is engaged with the head of the stud, the curved resilient fingers present guiding surfaces which afford an unobstructed guiding surface for engaging the socket over the head of the stud so that en- 85

105

110

gagement therewith may be effected very easily and quickly without the necessity of accurate engagement of the head of the stud with the stud-receiving aperture as is necessary when the stud-engaging fingers are not curved upwardly adjacent the stud-receiving aperture. The reversely bent neck-engaging portions, being formed at the upper surface, do not obstruct the entrance of the stud into the stud-receiving aperture as they do when presented at the lower surfaces of the resilient finger. Thus the socket herein illustrated may be guided over the head of the stud smoothly, and the resilient fingers will flex upwardly, without interference from the carpet, to permit passage of the head through the stud-receiving aperture 7 (Fig. 2) and engagement of the neck 12 of the stud by the neck-engaging portions 8 of the resilient fingers 4.

While I have shown and described a preferred embodiment of my invention, it will

be understood that I have done so for clarification and that my invention is best defined in the appended claim.

25

I claim:

A fastener socket having a stud-receiving aperture, a web surrounding said aperture and divided by a series of alternating short and long slots to provide a series of stud-engaging fingers surrounding said aperture, said fingers having their free ends terminating in a common plane adjacent to said aperture so that the free ends of all of said fingers may make fastening engagement with a neck of a cooperating stud and each of the fingers of the series surrounding the stud-receiving aperture having one lengthwise edge shorter than the other lengthwise edge 35 as and for the purposes described.

40

In testimony whereof, I have signed my name to this specification.

FRED S. CARR.
